OR D 3,396

W. H. Sadler.

Picture and Advertising Frame.

3396

PATENTED
MAR 2 1869

United States Patent Office.

WARREN H. SADLER, OF BALTIMORE, MARYLAND.

Design No. 3,396, dated March 2, 1869.

DESIGN FOR A PICTURE-FRAME.

The Schedule referred to in these Letters Patent and making part of the same.

To all whom it may concern:

Be it known that I, WARREN H. SADLER, of the city and county of Baltimore, and State of Maryland, have invented a new and improved Design for a Picture and Advertising-Frame; and I do hereby declare that the following is a full, clear, and exact description of the construction and operation of the same, reference being had to the accompanying drawings, forming a part of this specification, and in which my invention is represented by a front view.

This invention consists in a beautiful and ornamental design for a picture and advertising-frame, as herein-after set forth.

In the drawings—

A is the border of the frame, having a series of longitudinal mouldings or beadings, *a a a a a*.

B is the centre of the device, being nearly of a rectangular shape, plain, and adapted to receive any suitable inscription, card, picture, or other work of art.

This central space is surrounded with a border, C, as represented.

Between the border C C, of the central space, and the border A, of the whole apparatus, is a series of spaces, D D, adapted, like the central space B, to receive a card, picture, &c., and show the face thereof.

The border A is of wood, and the part between this border and the central space is of pasteboard, or other similar material, suitably covered, enamelled, or ornamented.

Through the openings B and D D, when the pictures, &c., are not inserted, the back-board of the apparatus may be seen.

Having thus described my invention,

What I claim as new, and desire to secure by Letters Patent, is—

The design for a picture and advertising-frame, as herein described and shown.

WARREN H. SADLER.
